UNITED STATES PATENT OFFICE.

HENRY H. GREENE, OF MILWAUKEE, WISCONSIN.

STOP-FASTENING.

SPECIFICATION forming part of Letters Patent No. 715,785, dated December 16, 1902.

Application filed November 25, 1901. Serial No. 83,526. (No model.)

To all whom it may concern:

Be it known that I, HENRY H. GREENE, a citizen of the United States, residing at Milwaukee, county of Milwaukee, and State of Wisconsin, have invented new and useful Improvements in Stop-Fastenings, of which the following is a specification.

My invention relates to improvements in fastenings for stops for windows, doors, &c.

10 The object of my invention is to provide means whereby the stop is made adjustable to the window and whereby it may be readily detached and removed without defacing either the window-frame or the stop.

15 In the following description reference is had to the accompanying drawings, in which—

Figure 1 is a detail view showing a portion of a window-frame equipped with my invention, with dotted lines indicating the position 20 of the holding-plate carried by the stop. Fig. 2 is a view of a portion of the inner face of the stop, showing the holding-plate. Figs. 3 and 4 are views similar to Figs. 1 and 2, respectively, but showing the holding-plate located on the window-frame and the locking-plate on the stop. Fig. 5 is a side view of a portion of a window-frame, showing the stop secured in position by two fastenings embodying my invention, the upper fastening corresponding with the construction shown in Figs. 1 and 2 and the lower fastening with the construction shown in Figs. 3 and 4. Fig. 6 is a sectional view drawn on line $x-x$ of Fig. 1.

Like parts are identified by the same reference characters throughout the several views.

Referring to Figs. 1 and 2, 1 is a locking-plate located in a suitable recess in the window-frame and provided with offset locking-lips 2, the shape of which locking-lips is 40 clearly shown in Fig. 6. The locking-plate is secured to the frame by a central screw 3, which serves as a pivot upon which the plate rotates. The window-stop 9 is provided with a holding-plate 4, which is rigidly secured to 45 the stop by screws 5, passing through the slots 6 in the plate, the slots permitting the plate to be adjusted transversely of the stop when the screws are loosened. This holding-plate is provided with offset catches 7 and also with 50 a projection 8, which bears against the rear side of the recess in the window-frame and holds the stop against the lateral pressure of

the window-sash. The holding-plate is secured to the stop in such a position that when the stop is adjusted to the window-frame the 55 holding-plate will register with the locking-plate, as indicated by dotted lines in Fig. 1, the projection 8 being of such length as to project into the recess of the locking-plate. When the locking-plate is moved in the direction indicated by the arrow in Fig. 1, the locking-lips 2 will interlock with the catches 7 and bind the stop firmly to the window-frame. By rotating the plate 1 in the opposite direction, however, the lips 2 are withdrawn from the catches 7, and the stop may be readily removed. It will be observed, Fig. 5, that the plate 1 is so located upon the window-frame as to project slightly beyond the edge of the stop on the side occupied by the window, the plate being covered by the window when the latter is closed. When the window is raised, however, the plate is exposed, as shown in said Fig. 5, and may be rotated to lock or unlock the stop by inserting a nail or other tool in holes 10 of the plate prepared for that purpose.

Referring now to Figs. 3 and 4, a plate 12, similar to the plate 1, (shown in Fig. 1,) is secured rigidly to the window-frame and is provided with offset catches 13. A locking-bar 14 is pivotally connected with the stop and provided with locking-lips 15, adapted to engage the catches 13. The bar 14 is actuated by means of a rod 16, connected therewith 85 and extending through the stop and provided with a thumb-piece 17 on the exterior. 18 represents pins projecting from the face of the stop-bar 9 and serve as stops for the bar 14.

Having thus described my invention, what I claim as new, and desire to secure by Letters Patent, is—

1. The combination with a window-frame, provided with a stop suitable for windows, doors, &c.; of a pair of locking-plates located 95 on the frame and stop respectively, one of said plates being rigidly secured to its respective support, and the other of said plates being adjustable independently of its support, whereby said plates may be brought into 100 locking engagement with each other, or to a position of release without moving either support, substantially for the purpose set forth.
2. The combination with a frame; a stop-

bar adapted to be adjusted thereto; interlocking plates interposed between the opposing faces of the stop-bar and the frame, and locked in a recess prepared therefor, one of said 5 plates being pivotally secured to one of the opposing faces, and the other plate being rigidly secured to the other opposing face; and means for actuating the pivotal plate into the locking and releasing positions.

10 3. The combination with a frame, provided with a stop-bar; of a locking-plate located in a suitable recess in the frame and exposed at one side of the stop-bar; locking-lips connected with said plate and offset therefrom; a holding-plate secured to the stop-bar and provided 15 with offset catches adapted to be engaged by the locking-lips, said locking-plate being formed for the engagement of a tool on the exposed side, whereby the plate may be adjusted into locking or releasing position.

4. The combination with a frame, provided with a stop-bar; of a locking-plate located in a suitable recess in the frame and exposed at one side of the stop-bar; locking-lips connected 25 with said plate and offset therefrom; a holding-plate secured to the stop-bar and provided with offset catches adapted to be engaged by the locking-lips, said holding-plate being provided with a stop adapted to engage 30 a straight-edged surface on the locking-plate, whereby the movement of the latter is limited; and said locking-plate being formed for the engagement of a tool on the exposed side, whereby the plate may be adjusted into locking 35 or releasing position.

5. The combination with a window-frame, provided with a stop suitable for windows, doors, &c.; of a pair of interlocking plates located on the opposing surfaces of the frame 40 and its stop; means for moving one of said plates into the locking and releasing positions; and means for adjusting the stop-plate laterally, to bring the stop into forcible contact with the window-sash.

6. The combination with a window-frame 45 provided with a stop suitable for windows, doors, &c.; of a locking-plate located in a suitable recess in the window-frame; a holding-plate located on the stop, and provided with interlocking projections adapted to be 50 engaged by the locking-plate; and a projection on the holding-plate adapted to engage in the frame-recess to hold the stop firmly against the window-sash.

7. The combination with a frame; of a stop-bar adjustable thereto; and a set of locking-plates mounted respectively upon the opposing faces of the frame and bar, one of said plates being rigidly secured in position, and the other being adjustably mounted upon its 60 respective support, said plates being provided with interlocking parts, adapted to separate when the adjustable plate is moved in one direction.

8. The combination with a frame; of a stop-bar adjustable thereto, with the opposing faces of the frame and bar in contact with each other; an adjustable locking-plate mounted upon one of the opposing faces of said plate, and adapted to be adjusted independently of the frame or bar; and a locking-catch on the other of said opposing faces. 65

9. The combination with a frame; of a stop-bar adjustable thereto; and a set of locking-plates mounted respectively upon the opposing faces of the frame and bar, and adjustable, one upon the other, independently of the frame or bar, said plates being formed to interlock when in one position of adjustment; together with means for actuating one of the 70 plates from the exterior. 75

In testimony whereof I affix my signature in the presence of two witnesses.

HENRY H. GREENE.
